FOREIGN PATENT DOCUMENTS

FR 2 486 855 1/1982

Primary Examiner—Terry A Wallace

(74) Attorney, Agent, or Firm—McDermott Will & Emery

(57) **CLAIM**

We claim the ornamental design for a zester, as shown and described.

DESCRIPTION

FIG. 1 is a perspective view of a zester according to the new design;

FIG. 2 is a front view of a zester shown in FIG. 1;

FIG. 3 is a top view of a zester shown in FIG. 1;

FIG. 4 is a rear view of the zester shown in FIG. 1;

FIG. 5 is a bottom view of a zester shown in FIG. 1;

FIG. 6 is a left side view of the zester shown in FIG. 1; and,

FIG. 7 is a right side view of the zester shown in FIG. 1.

Features shown in broken lines form no part of the claimed design.

1 Claim, 3 Drawing Sheets
